COMBINED ASH TRAY, GAME SPINNER, AND SCORING CHART OR SIMILAR ARTICLE

James Babcock, Pomona, Calif., assignor to James Babcock Associates, Inc., Beverly Hills, Calif., a corporation of Nevada

Application February 18, 1955, Serial No. 34,574

Term of patent 3½ years

(Cl. D85—2)

Figure 1 is a perspective view of a combined ash tray, game spinner and scoring chart or similar article, showing my new design;

The broken line showing of legible matter in the drawing figures is for illustrative purposes only. Portions of the drawing figures are lined to indicate color contrast.

I claim:

The ornamental design for a combined ash tray, game spinner and scoring chart or similar article, substantially as shown and described.
